UNITED STATES PATENT OFFICE.

PHILLIP R. GEORGE, OF CHICAGO, ILLINOIS.

PEN AND PENCIL GRIP.

1,411,691.

Patented Apr. 4, 1922.

Application filed July 2, 1920. Serial No. 393,682.

To all whom it may concern:

Be it known that I, PHILLIP R. GEORGE, a citizen of the United States, residing at Chicago, in the county of Cook and State 5 of Illinois, have invented certain new and useful Improvements in Pen and Pencil Grips, of which the following is a specification.

This invention relates to calligraphic devices and more particularly to an improved grip for pens or pencils and designed by its presence to cause the writer to hold the pen or pencil in what is accepted as the proper position for use.

One of the primary objects of the invention is to so construct the grip that it will, to the desired extent, prevent manipulation of the pen or pencil through movement of the joints of the fingers and thumb so that 15 the user will be influenced to manipulate the pen or pencil practically solely with a wrist movement. Thus the invention is designed to not only teach those learning to write the proper position in which to hold 20 the pen or pencil and the proper manner in which to manipulate the same but also to serve as a means for assisting experienced writers and preventing them from acquiring inaccurate hand and finger movement in 25 writing. Likewise the invention is designed 30 to prevent the user being afflicted with writer's cramp.

In the accompanying drawings:

Figure 1 is a perspective view illustrating one form of the device applied to a pencil and illustrating in dotted lines the manner in which the hand is to grip the device;

Fig. 2 is a view in elevation looking at one side of the device;

Fig. 3 is a transverse sectional view on the line 3—3 of Fig. 2;

Fig. 4 is a plan view of the sheet metal blank from which the device is formed;

Fig. 5 is a view similar to Fig. 3 illustrating a modified form of the invention.

The device embodying the present invention is preferably formed from sheet metal such for example as aluminum although any other kind of metal or any other material 50 suitable for the purpose may be employed. Also the device is preferably formed from

a single integral sheet blank which has the general form illustrated in Fig. 4 of the drawings. This blank comprises a portion which is indicated in general by the reference letter A and a portion B, and in forming up the device from the blank the blank is bent along the line of juncture C of its two portions A and B so that the portion B will extend perpendicularly across one face of the portion A. The said portion B is bent up to substantially cylindrical form with its lateral edges nearly meeting, so as to form a sleeve 1 which is open at one side as indicated by the numeral 2 so that the sleeve may be fitted to practically any ordinary pen or pencil and may suitably expand if the pen or pencil is of large diameter, the sleeve being thus adapted to fit pens or pencils of various cross-sectional 60 diameters and being capable of adjustment longitudinally thereof and being frictionally held in its positions of adjustment. At its end opposite its end which is joined to the portion A, the portion B is provided with a 65 tongue 3 which is overturned as at 4 about that edge of the portion A opposite the edge at which the portion B is joined to the said portion A. In this manner the sleeve is firmly joined and secured to the portion A 70 so in position extending perpendicularly of one face thereof.

The portion A in blank form is marginally of reniform contour and at one side of the sleeve 1 is gradually bent upon itself 75 along a line diagonal to the longitudinal median line of the blank and indicated approximately at D in Fig. 4, to provide a wing 5 having an open side presented in the general direction of the sleeve 1 and located at the same side of the body of the portion A as is the said sleeve. This wing 80 5 is broader at its upper portion than at its lower portion and is designed to more or less snugly fit and partly embrace the forefinger 90 of the hand at and adjacent the first joint of the said finger, the sleeve 1 extending beside the finger between the tip and the second joint so that the pen or pencil which is fitted into the sleeve will extend upwardly across 95 the forefinger between the second joint and the knuckle, the intermediate part or body 100

of the portion A of the device, when the device is so applied, occupying approximately a vertical plane.

The body portion A at the opposite side 5 of the sleeve 1 is bent more or less sharply upon itself as indicated by the numeral 6 so as to provide a portion 7 which is approximately flat and which lies relatively close to the outer face of the body portion A, and 10 a portion 8 which is curved upwardly and outwardly from the plane of the body portion A and provides a rest for the ball of the thumb.

It will be understood that the device may 15 be fitted onto any ordinary pen or pencil and that when so applied the forefinger may be engaged beneath the wing 5 and the thumb may be brought to bear against the thumb rest 8 adjacent the relatively flat portion 7 of the device and that when so grasped the pen or pencil will be caused to assume the proper angle with relation to the hand of the writer and he will be influenced to write with a wrist movement inasmuch as 20 the wing 5 so confines the first joint of the forefinger as to prevent flexing of this joint.

In that form of the device shown in Fig. 5 of the drawings, the device comprises a sleeve 9 corresponding to the sleeve 1, a wing 5 30 10 corresponding to the wing 5 and a wing 11 which takes the place of the parts 7 and 8 comprising the thumb rest of the first described form and which wing 11 is curved laterally outwardly and thence upwardly 35 with relation to the plane of the body portion A of the device and which is open at its upper side and is designed to receive and fit the thumb. Of course, in this latter form of the device the thumb will be positively 40 engaged and partly embraced by the wing 11 and therefore retained in its proper position whereas in the first described form of the device the thumb is to be held against the thumb rest comprising the said portions 45 7 and 8. Otherwise the two forms of the device are substantially identical.

It will be understood that when the device is applied to a penholder it will constitute also a means for holding the pen 50 point clear of a surface upon which the penholder and device are disposed.

Having thus described the invention, what is claimed as new is:

1. A device of the class described comprising a body portion having its ends bent in opposite directions to form wings for engagement with the index finger and thumb respectively, and a sleeve arranged on one side of the body portion for the reception of 55 a writing instrument and provided at one end with a terminal tongue engaging the opposite side of said body portion.

2. A device of the class described comprising a body portion having its opposite

ends bent to form wings disposed on opposite sides thereof for engagement with the forefinger and thumb respectively, and a cylindrical sleeve arranged on one side of the body portion and of equal width therewith for the reception of a writing instrument, one end of the sleeve being formed integral with the body portion and the other end thereof provided with a tongue bent into engagement with the opposite side of said body portion for holding the sleeve 75 against accidental displacement.

3. A device of the class described comprising a body portion having one end thereof curved laterally to form a wing for engagement with the index finger and its opposite 80 end bent in substantially parallelism with the opposite side of the body portion and thence extended laterally to form a wing for engagement with the thumb, and a substantially cylindrical split sleeve arranged 85 on one side of the body portion and having one end thereof formed integral with said body portion and its other end provided with a tongue extending over the adjacent edge of the body portion and bearing 90 against the opposite side thereof for holding the sleeve against displacement.

4. A device of the class described comprising a body portion wider than it is long and having its opposite side edges bent in opposite directions to form wings for engagement with the forefinger and thumb respectively, and a split cylindrical sleeve disposed on one side of the body portion and of the same width as said body portion for the reception 100 of a writing instrument, one end of the sleeve being formed integral with the body portion and the other end thereof provided with a tongue extending over the adjacent edge of said body portion and in contact 105 with the other side thereof.

5. A blank for pen and pencil grips comprising an elongated body portion having a substantially rectangular portion connected therewith by reduced neck and disposed at 110 substantially right angles thereto, said rectangular portion being formed with a terminal tongue, the ends of the body portion being adapted to be bent in opposite directions to form wings and the rectangular portion 115 being adapted to be bent into substantially cylindrical form and folded against one face of the body portion with the tongue bent over the edge thereof and in contact with the other face of said body portion.

6. A blank for pen and pencil grips comprising an elongated body portion having its upper edge curved in an arc from one end to the other and having its lower edge straight and connected by a reduced neck 125 with a substantially rectangular portion arranged at right angles to said straight edge, the lower end of the rectangular portion be-

ing formed with a tongue, the ends of the body portion being adapted to be bent laterally in opposite directions to form wings for engagement with the thumb and 5 forefinger respectively, and the rectangular portion being adapted to be bent into substantially cylindrical form and folded at

said reduced neck against one side of the body portion with the tongue bent over the curved edge of said body portion and in contact with the other side thereof. 10

In testimony whereof I affix my signature.

PHILLIP R. GEORGE [L. s.]
